(57) CLAIM

The ornamental design for golf club head, as shown and described.

DESCRIPTION

FIG. 1 is a perspective bottom view of a golf club head
showing our design;

FIG. 2 is a bottom plan view thereof;

FIG. 3 is a top plan view thereof;

FIG. 4 is a toe end view thereof;

FIG. 5 is a heel end view thereof;

FIG. 6 is a front elevation view thereof; and

FIG. 7 is a rear elevational thereof;

FIG. 8 is a perspective bottom view of a golf club head in accordance with a second embodiment of our invention
showing our design;

FIG. 9 is a bottom plan view of FIG. 8;

FIG. 10 is a top plan view of FIG. 8;

FIG. 11 is toe end view of FIG. 8;

FIG. 12 is a heel end view of FIG. 8;

FIG. 13 is a front elevation view of FIG. 8; and,

FIG. 14 is a rear elevational of FIG. 8.

The dash-dash and dash-dot broken lines show portions of the golf club head and form no part of the claimed design.

1 Claim, 10 Drawing Sheets
